ATTACHMENT MEANS FOR CONVEYER FLIGHTS

Arthur C. Lind, Milwaukee, Wis., assignor to
Chain Belt Company, Milwaukee, Wis., a corporation of Wisconsin.

Application June 29, 1944, Serial No. 542,701

5 Claims. (Cl. 198—194)

1

The invention relates to means for readily detachably securing baskets, buckets, flights and similar elements to conveyor chains, and for purposes of disclosure it has been illustrated in the accompanying drawing in connection with the mounting of the screen baskets of endless traveling water screen of the type disclosed in prior U. S. Patents No. 1,781,223 granted Nov. 11, 1930, and No. 1,856,381 granted May 3, 1932, on applications filed by Francis P. Gary. The invention also constitutes a further development of the attachment arrangement disclosed and claimed in U. S. Patent No. 2,286,332 granted June 16, 1942, on an application filed by Lloyd G. Bleyer.

The invention has for its principal object the provision of a simple and effective construction for the attachment of water screen baskets and similar elements to the endless chains which carry them, which construction may not only be produced and assembled relatively inexpensively, but also strengthens the assembly and substantially eliminates undesirable play therein which would tend to hasten wear on the parts. At the same time, should such wear ultimately occur, or should the chains, baskets or attachment means become damaged whereby replacement of any of the elements be necessary, the baskets and/or the parts of the attachment means may be readily removed and replaced in the field without the use of any special tools or machines.

In the accompanying drawing forming a part of this specification, in which like reference characters designate like parts throughout the views:

Figure 1 is a fragmentary rear elevational view of one unit of a traveling water screen of the type mentioned above, showing one end of the screen basket assembly of such unit secured to a link of one of the endless supporting chains by one form of attachment means constructed and arranged in accordance with the present invention;

Fig. 2 is a vertical sectional view on approximately the plane indicated by the line 2—2 of Fig. 1, looking in the direction of the arrows;

Fig. 3 is a partial front elevational view of the unit, as seen from the right of Fig. 2;

Figs. 4 and 5 are cross sectional views taken respectively on the planes indicated by the lines 4—4 and 5—5 of Fig. 1, looking down;

Fig. 6 is a perspective view of one of the attachment blocks which are carried by each of the chain links.

Fig. 7 is a rear elevational view of a slightly modified form of attachment bracket;

Fig. 8 is a central vertical sectional view of the bracket shown in Fig. 7; and

2

Fig. 9 is a side elevational view of a modified link-carried pin or block for use with the bracket shown in Figs. 7 and 8.

As in the several prior patents referred to above, the screen basket assembly comprises laterally spaced end plates 10 (of which only one is here shown) which are rigidly connected by the vertically spaced transverse members 11 and 12 to form a hollow rectangle within which the screen 13 is secured by the clamping bars 14 and bolts 15. To the outer face of each end plate 10 there is secured a projecting shelf 16, conveniently formed of stamped sheet metal and welded as at 17 to the said plate face. In the operation of the screen 15 these shelves co-operate with fixed guides and prevent passage of trash, etc., around the ends of the screen baskets, as is more fully explained in the aforesaid Patents Nos. 1,781,223 and 1,856,381.

The spaced strands of chain to which the baskets are attached comprise relatively long-pitch links 20, each of which includes a pair of spaced side bars 21 inset at one end 22 where they are rigidly connected together by a press-fitted bushing 23 upon which is journaled a chain roller 24. At their other end the side bars are provided with apertures 25 for registry with the bore of the bushing 23 of the next adjacent link whereby the links may be articulately connected by chain pins (not shown) passed through and suitably retained in the registering apertures and bushing bores.

As in the said prior patents, each screen unit is secured at each of its ends to a link of the adjacent carrying-chain strand by connections between 35 the shelves 16 and the said links 20. In the form shown in Figs. 1—6 inclusive the present connections comprise a bracket 30, which may be of malleable iron or equivalent material, which is secured by rivets 31 against the rear face of the 40 shelf 16 intermediate the ends of the latter. The rear face of this bracket is provided with a pair of vertically spaced projecting parallel flanges or lips 32 extending the full width of the bracket and providing between them an elongated rearwardly open partly-cylindrical or tapering socket 33 which is adapted to snugly receive the body of a generally cylindrical block or bridging member 34, which however may be provided with a flat surface 35 extending from end to end thereof. 45 The end portions of the said block are also provided with short flats 35' disposed opposite to the said surface 35, and said end portions are press-fitted into complementary aligned openings 36 provided in the side bars 21 of the chain link 20 50 intermediate the ends thereof. The block 34 is

provided with a threaded hole 37 for reception of a securing bolt 38 whereby the parts may be detachably secured in the positions shown, with the body of the block drawn into and firmly seated in the socket or recess 33 and the lips 32 in intimate engagement with the surface of the said body throughout substantially its entire length.

Filler pads 40 of sheet metal are preferably interposed between the rear face of the shelf 16 and the forward faces of the chain side bars 21, intermediate the bracket 30 and the respective ends of the shelf. The weld 17 between the shelf and the end plate 18 of the basket structure may extend throughout the length of the contact between the two members, but preferably such weld is omitted in the area between the filler pads 40 so that the portion of the shelf between such pads is free to yield slightly as the bolt 38 is drawn home, thus placing this portion of the shelf under tension.

The block 34, being rigidly press-fitted into the apertures 36 of the chain side bars 21 intermediate their ends, obviously strengthens the chain construction by providing a bridge or tie between such bars in addition to that normally provided by the bushing 23. The said block also serves as a chain driving lug, being engageable by the teeth such as 45 (Fig. 2) of the head and foot sprockets of the screen.

The intimate engagement between the body of the block 34 and the elongated lips 32 takes all shearing strains off the attachment bolt 38, and also prevents any twisting of the basket structure relative to the chain link about the axis of such bolt. The basket units are readily demountable from the chains in case of necessity, by merely removing the one bolt 38 at each end of the unit, which may be accomplished by means of an ordinary socket wrench. So far as the attachment elements are concerned, no welding operations are employed so that such elements are easily removable and renewable if necessary.

In the modified form of construction illustrated in Figs. 7, 8 and 9, the bracket 50 is provided with a frusto-conical socket 51 in lieu of the rectangular socket described above, and bridge or tie block 52 of the chain link is provided with a complementary frusto-conical projection 53 extending outwardly from its flattened surface 54. As will be readily understood, the projection 53 will be received in the socket 51 and firmly seated therein when a bolt, such as 38, is passed through the aperture 55 and screwed into the threaded hole 56 of the block. While still accomplishing the desired simple yet firm attachment of the screen baskets to the chain links, this modified construction will permit of slight pivotal movement between the baskets and links about the axes of the bolts 38, i. e., in a plane at substantially right angles to that of link articulation, which relieves twisting strains upon the baskets should one strand of the carrying chains tend to run somewhat ahead of or behind the other strand, as they sometimes do.

While two forms of the invention have been illustrated and described, it will be obvious that those skilled in the art may further vary the details of construction as well as the precise arrangement of parts without departing from the spirit of the invention, and therefore it is not wished to be limited to the above disclosure except as may be required by the claims.

What is claimed is:

1. In conveyer or like structure, the combination of a chain, a material-conveying element

having an end member adjacent one of the chain links; a shelf member secured to and extending from said end member across said link; and means for readily detachably connecting the conveying element to the link, comprising interfitting members rigidly carried respectively by the link and by a portion of said shelf member, and a bolt for drawing said interfitting members into and maintaining them in operative engagement; the portion of said shelf member adjacent said connecting means being unattached to said end member of the conveying element whereby said shelf portion may yield slightly as said bolt draws the interfitting members home.

15 2. In conveyer and like structure, a sprocket chain having a link comprising a pair of transversely spaced side bars; a material-conveying element disposed laterally adjacent said link and having a portion extending across said side bars, which portion is provided with an open faced socket; a member bridging the space between the side bars and rigidly secured to the latter; and means for seating and readily detachably securing said bridging member in the socket.

20 3. In conveyer and like structure, a sprocket chain having a link comprising a pair of transversely spaced side bars provided with aligned apertures; a material-conveying element positioned laterally adjacent said link and having an extension disposed across the side bars, which extension is provided with a tapered socket; a member bridging the space between the side bars and having its ends rigidly secured in said apertures of the latter; and means for readily detachably retaining said bridging member in engagement with the walls of said socket.

25 4. In conveyer and like structure, a sprocket chain having a link comprising a pair of transversely spaced side bars; a material-conveying element positioned laterally adjacent said link and having an extension disposed across the side bars, which extension is provided with an elongated socket having converging side walls; a substantially cylindrical member bridging the space between the side bars and having its end portions rigidly secured to the latter; and means for readily detachably retaining said bridging member in engagement with said side walls of the socket.

30 5. In conveyer and like structure, a sprocket chain having a link comprising a pair of transversely spaced side bars; a material-conveying element positioned laterally adjacent said link and having an extension disposed across the side bars, which extension is provided with a coniform socket; a member bridging the space between the side bars and rigidly secured to the latter, said member having a coniform projection for reception in said socket; and means for readily detachably retaining said projection seated in said socket for pivotal movement between the two.

ARTHUR C. LIND.
